UNITED STATES PATENT OFFICE.

ROBERT DUTHIE, OF NEAR CHRISTCHURCH, NEW ZEALAND.

COMBINATION MOISTURE REMOVER AND GLARESHIELD FOR TRANSPARENT LOOKOUT SCREENS OF MOVING BODIES.

Application filed October 12, 1925, Serial No. 62,054, and in New Zealand November 27, 1924.

This invention relates to a device designed primarily for employment upon wind-screens such as those of motor-cars but applicable also to other forms of transparent screens such as the windows of tram or railway cars, locomotives or windows on board ship.

The outer surfaces of such screens are apt, when exposed to the weather, to become 10 coated with moisture due to the presence of fog or to the driving of rain or snow against such surfaces, with the result that such screens become for the time being more or less opaque.

15 According to a previous invention of mine there was employed upon such screens a hollow vessel comprising a mouth adapted to come in contact with the air currents produced by the motion of the vehicle or ship, and an outlet of relatively smaller area than the said mouth and arranged to deliver air, collected by the latter, against the said screen in a direction more or less parallel therewith in order that such discharge may 20 remove the abovementioned coating from the said screen.

According to my said invention also it was proposed to arrange the said device along the upper portion of the screen in 30 order that its underside might serve also as a hood or glare-shield as frequently provided upon wind-screens to shade the same from the direct rays of the sun and thus ensure a clear look-out through such screens 35 in bright weather.

It is the object of the present invention however to provide a device of this nature of novel and special construction whereby the same when not required for use in removing the moisture coating, may, by a simple and convenient manipulation, be collapsed or folded together into a condition in which it will serve only as a glare-shield and present a neat and sightly appearance.

45 In order that the nature of the invention and its construction may be clearly understood, it will now be fully described and explained with reference to the accompanying drawings, in which:

50 Fig. 1 is a perspective view of a motor-car wind-screen fitted with the invention which is shown in full lines in its closed or collapsed condition, while its corresponding open or extended condition is indicated in dotted lines,

Fig. 2 is a front elevation upon a somewhat larger scale showing the device in its open or extended condition,

Fig. 3 is a cross section along the line III—III, Fig. 2, and,

Fig. 4 is an end-elevation of the device in its closed condition.

The device which is adapted to be mounted along the upper portion of a screen as 1, comprises a pair of horizontal sides or 65 members 2 and 3 arranged one above the other and adapted when the device is in its extended condition to serve as a moisture remover, to converge gradually from an inlet-mouth 4 constituted by the space or interval between the forward edges of the members 2 and 3, to a throat 5 at the rear portion of the device and which throat terminates in a narrow outlet 6 through which the air passing through the said device is 75 discharged against the surface of the screen 1.

According to the present invention one of the said horizontal members, preferably the lower member 3, is made integral with the 80 throat portion 5, or rigidly secured thereto, while the other horizontal member 2 is connected by means of a hinge as 7 to such throat portion to permit of such hinged member being arranged in its said converging relation to the member 3, as here shown in Figs. 2 and 3 and in dotted lines Fig. 1, or being collapsed or folded towards the other said member, as shown in Figs. 1 and 4 when the device is not required for use as 90 a moisture remover.

The construction includes also a pair of members 8 and 9 adapted when the structure is in its extended position, to lie vertically and enclose the structure at its two 95 lateral sides.

The lateral members 8 and 9 are each connected by means of one or more hinges as 10 with one of the horizontal members, preferably the member 3 as here shown, to 100 permit of such lateral members being turned upon their said hinges into their vertical or substantially vertical positions to enclose the ends of the device when in the extended condition, or to be folded inwardly to lie 105 in horizontal positions between the two members 2 and 3 when the latter occupy their collapsed or folded together condition as already explained.

In the preferred form of the construc- 110

tion the lateral members will be provided with springs as 11 which tend to place and retain them in their vertical positions and suitable catch means may also be provided 5 upon the inner surface of one of the horizontal members to engage the lateral members and retain the latter in their said horizontal positions when the device is folded.

The horizontal members will also be provided with one or more springs tending to cause the hinged member to turn upon its hinge 7 in the direction away from its fellow. In the preferred form of the construction as here shown this is effected by providing the hinged member 2 with one or more arms as 12 each projecting downwardly and having its lower end connected with one end of a spring as 13 the other end of which is connected with the member 3.

20 The horizontal member 3 is preferably formed at each of its lateral edges with a flange as 14 extending vertically towards the member 2 such flanges constituting continuations of the lateral enclosing sides of the 25 throat 5 and being arranged to lie to the outer sides of the lateral members 8 and 9 and receive the latter when the device is in its extended condition.

The member 2 is also preferably provided 30 at its lateral edges with vertically disposed flanges 15 arranged to lie to the outer sides of and overlap the flange 14 when the device is in its folded condition and to receive and limit the outward movement of the lateral members 8 and 9 when the device is in 35 its extended condition.

The throat-portion 5 will preferably be down-turned in order to place its outlet 6 in the required position to discharge the 40 air downward against the surface of the screen 1. There will also preferably be provided a baffle plate as 16 arranged to extend horizontally at a slight interval beneath the outlet 6 in order to deflect the air 45 from the latter against the said screen.

The lower horizontal side 3 will preferably be curved downward towards the mouth or forward portion of the device as here shown to provide an appropriate undersurface 50 for the glare-shield and the upper member 2 will also be suitable down-curved as shown to neatly overlie the member 3 when the device is in its collapsed condition.

The upper member 3 will also preferably 55 be formed at its forward edge with a spout or channel as 17 to catch and convey to the lateral sides of the device any water that may run down the upper surface of the member 3.

60 The device will be attached to the wind-screen by suitable means which will preferably be such as to permit of the angle of such device being adjusted in relation to the screen to obtain the most favourable results 65 when the device is employed as a glare-

shield. In the preferred form of the construction as here shown the said means of attachment consists of a pair of brackets or members 18 adapted to be secured to the upper edge of the wind-screen and connected 70 by hinges as 19 with the rear side of the throat portion of the device.

Suitable means will be provided also for enabling the device to be conveniently retained in either its expanded or collapsed 75 condition and for enabling such device as a whole to be adjusted upon its said hinged connection to the screen so as to extend therefrom at a desired angle.

For this purpose in the preferred form of 80 the construction, as here shown, there is provided, at each lateral end of the device, a link or member 20 attached to its upper end as by means of a pivot 21 to the horizontal member 3 or its flanges 15, each of the said links 20 being arranged to project downward for a suitable distance and being formed with a slot 22 extending longitudinally therewith and through which slot extends a screw or stud 23, attached, as by 85 means of a bracket 24, to the lower horizontal member 3.

Upon the screw or stud 23 is received a wing-nut or the like 25 by means of which such screw may be clamped in any desired 90 position within the slot 22.

There is provided also a second pair of links or stays 26 adapted to connect the studs 23 with the corresponding lateral sides of the wind-screen. For this purpose each of the said stays 26 is formed near one end thereof with a longitudinal slot 27 through which extends one of the studs 23, while near its other or reverse end such stay is formed with a second longitudinal slot 28 to receive 100 a stud 29 projecting from the side of the wind-screen and provided with a clamping nut 30.

In operation when the device is required 105 to serve as a glare-shield the horizontal members 2 and 3 will be brought together by folding upon the hinge 7 and the lateral members 8 and 9 folded inward upon their hinges 10 so as to lie horizontally between the said members 2 and 3 the device being 110 retained in this condition as by means of the studs 23 and their nuts 25, the angle of the device in relation to the screen being adjusted by means of the studs 29 and their 115 nuts 30.

When it is desired to employ the device 120 as a moisture-remover however the nuts 25 will be slackened thereby enabling the links 20 to move upward and so allow the member 2 being turned upward upon its hinge 7 and the side members 8 and 9 turned into their vertical positions, thus providing the mouth 125 4 adapted to receive air which is discharged through the outlet 6 against the surface of 130 the screen.

I claim:—

1. A device of the nature indicated for attachment to a transparent screen upon a moving body and comprising a pair of horizontal side members arranged one above the other, a throat portion forming the rear termination of one of said members and having a narrow out-let arranged to discharge air from said throat against the surface of said screen, a hinge connecting the rear edge of the other said horizontal member with said throat portion thereby to permit of said members being placed in one position in which the forward edge of one member will closely overlie the other said member and in another position in which the said members will lie at an interval apart to provide a mouth adapted when the said body is in motion to collect air and deliver the same to the said throat portion, and means for enclosing the spaces between the said horizontal members at each of the lateral sides of the device when the said horizontal members occupy their said position at an interval apart.

2. A device of the nature indicated as defined in claim 1 characterized in that the said horizontal members are arranged when occupying their said position at an interval apart to converge gradually from their forward edges to the said throat.

3. A device of the nature indicated as defined in claim 1 characterized in that the said means for enclosing the lateral spaces between the horizontal members comprise a pair of side members each hinged to one of the said horizontal members thereby to permit of said lateral members being turned into substantially vertical positions to enclose the said spaces when the horizontal members lie apart and into horizontal positions to lie between the said horizontal members when the latter are in their other or collapsed relation.

4. A device of the nature indicated as defined in claim 1, characterized in that the said means for enclosing the lateral spaces between the horizontal members comprises a pair of side members each hinged to one of the said horizontal members to permit of such lateral members being turned into substantially vertical positions when said horizontal members lie apart and into horizontal positions to lie between said horizontal members when the latter are in their other or collapsed relation and in that said lateral members are provided with springs tending to place them in their said vertical positions.

5. A device of the nature indicated as defined in claim 1 characterized in that the said horizontal members are provided with springs tending to carry them into the said position in which they lie apart.

6. A device of the nature indicated as defined in claim 1 characterized in that each of the said horizontal members is provided at its lateral edges with flanges projecting towards the other said horizontal member.

7. A device of the nature indicated as defined in claim 1 characterized in that the lower of said horizontal members is down curved at its forward portion.

8. A device of the nature indicated as defined in claim 1, characterized in that the said throat is of gradually diminishing area to its said outlet.

9. A device of the nature indicated as defined in claim 1 characterized in that the said throat is down-turned to its said outlet.

10. A device of the nature indicated as defined in claim 1 characterized in that a baffle plate is provided and arranged to extend horizontally beneath the said outlet to direct the air issuing from the latter onto the surface of the screen.

11. A device of the nature indicated as defined in claim 1 characterized in that the upper of said horizontal members is provided at its forward edge with a channel adapted to receive any moisture that may run down the upper surface of the said member and to deliver the same at the lateral sides of the device.

12. A device of the nature indicated as defined in claim 1 characterized in that the said device is attached to the screen by means of a hingeable connection thereby to permit of the angle of such device being adjusted in relation to the said screen.

13. A device of the nature indicated as defined in claim 1 characterized in that the said horizontal members are connected by means for the purpose of retaining such members in either of their said positions.

14. A device of the nature indicated as defined in claim 1 characterized in that one of the said horizontal members is provided at each of its lateral sides with a link having a longitudinal slot wherein is received a screw connected with the other horizontal member and adapted to clamp the said link thereby to retain the said member in each of their said positions.

In testimony whereof I have signed my name to this specification.

ROBERT DUTHIE.
